PACKAGE AND ARTICLE HANDLING
IMPLEMENT

Carl Hellwig, Cali, Colombia

Application January 23, 1934, Serial No. 707,963

13 Claims. (Cl. 294—22)

My invention is an implement for placing packages, cartons, canned and tinned goods, bottles, etc., on high shelves and removing the same therefrom, thus making the use of stepladders 5 unnecessary.

Generally the implement comprises a platform, preferably of rhomboid shape, mounted on the end of a pole and provided with a stationary tongue and an adjustable hinged tongue, the latter being spring held in the "open" or rest position, means being provided and operated manually for moving the hinged tongue down over the article to be manipulated after the stationary tongue has been slipped beneath the article, thereby to clasp the article between the two tongues.

The invention also provides a horizontally disposed hook carried by the platform and extending from an end of the same, by means of which 20 hook objects may be moved sidewise on the shelf and bottles laid horizontally or set upright as desired.

The invention has for an object to produce an implement, having the aforesaid general characteristics, of a simple and inexpensive construction and one which will readily and effectively serve its intended purposes.

Other objects will in part be obvious and in part be pointed out hereinafter.

20 To the attainment of the aforesaid objects and ends, the invention still further resides in the novel details of construction, combination and arrangement of parts, all of which will be first fully described in the following detailed description, then be particularly pointed out in the appended claims, reference being had to the accompanying drawing in which:

Figure 1 is a perspective view of my invention.

Figure 2 is a central vertical section of the 40 same.

Figure 3 is a horizontal section on the line 3—3 of Figure 2.

Figure 4 is a cross section on the line 4—4 of Figure 2, showing a modification.

45 Figure 5 is an inverted plan view on a small scale of a modified construction of platform.

Figure 6 is a section on the line 6—6 of Figure 5.

In the drawing in which like numerals of reference indicate like parts in all the figures, 1 represents a pole, preferably made of wood or metal sections, secured together by suitable separable 50 couplings 2 so that the pole may be lengthened or shortened as desired.

55 On the upper end of the pole 1 is mounted

a platform 3 preferably of rhomboid shape. The platform has a hole 4 to receive the reduced end 5 of the pole 1. The rear portion of the platform 3 is recessed to receive the upper end of a vertical block 6 which is secured to the platform 3 and to a spacer block 7 by suitable screws 9, or in any other suitable way. The spacer block 7 is secured at 8 to the pole 1; thus the platform 3 is rigidly mounted on the pole 1 and the block 6 comprises a suitable upright support for the vertically adjustable slotted bar 12 which is secured to the block 6 by bolts 10 and nuts 11. The bolts 10 pass through the longitudinal slot 13 as shown in Figure 2.

The bar 12 is preferably formed of metal such as aluminum and has its upper end enlarged at 14 to receive a shelf 15 which is suitably secured in any well-known way to the enlargement 14 and to the shelf 15 is secured a spacer block 16 to which the hinge 17 is secured, the hinge 17 being also secured to the movable tongue 18.

The movable tongue 18 is held in its lifted position by means of a spring 19 secured to the block 16 and connected with the tongue 18 by a suitable strap 20.

The tongue 18 is preferably tapered toward the free end, and at the free end it carries a toothed disc 21. The tongue 18 is provided with eyes 22 at each side to which the operating cords or cables 23 are secured. The cords or cables 23 pass through guide eyes 24 at the side ends of the platform 3 and through an eye 25 on the pole 1, there being a pull ring 26 secured to the ends of the cables 23.

27 is a stationary tongue secured at 29 to the 90 platform 3. The stationary tongue is preferably made of light wood and covered either by a metal sheath 28 or a felt surface, as desired. The tongue 27 may be straight, as shown in Figures 1 and 2, or concave, as shown in Figure 4, the latter form being preferable where the instrument is to be used principally in handling bottles and other round objects. The tongue 27 projects beyond the platform 3 and terminates in one or more fingers 31 to facilitate the entry of the 100 tongue between the shelf and the package 32 in operating the device. In Figure 4 the tongue 27a is shown concaved as at 30, the sheathing being indicated by 28a.

The object to be removed from the shelf is 105 worked out sufficiently to enable the tongue 27 to be placed under it and by pulling the ring 26 the cables 23 bring the tongue 18 down (see dotted lines in Figure 2) so that it will grasp the article 32. By tilting the implement backwards some- 110

what before grasping it tight with the tongue 18 the article 32 will slide completely upon the tongue 27, after which tongue 18 is pulled tight and the object may then be safely taken down.

5. In order to put the article back in its place upon the shelf the article is placed on the tongue 27 and grasped by pulling down the tongue 18. The pole is then raised to the proper height and the tongue 27 is placed on the shelf. The implement is then tilted slightly forwards and the tongue 18 is released, whereupon the article may be slipped off the tongue 27 onto the shelf where it may be adjusted as to position by manipulating the implement, using the fingers 31 of the tongue 15 27 or the hook 33.

Upright standing bottles must be first tilted horizontally by the use of the hook 33. They may then be taken down by grasping them between the tongues 27 and 18.

- 20 Tongues 27 may be made in various sizes and forms, depending upon the specific use to which they are to be put. These tongues may be used interchangeably on the platform 3 as desired. Other suitable means than screws 29 may be used 25 removably to secure the tongue to the platform, as may be found convenient.

The platform 3, instead of being diamond-shaped in plan, may be shaped as indicated in Figures 5 and 6, from which it will be seen that 30 the front portion of the platform 3a is of tongue-like form and is tapered on its under side as at 3x, thereby to assist in its easy movement into position beneath the packages or articles on the shelf.

- 35 The bar 12 may be formed integrally with the shelf, if desired, in order to reduce the cost of manufacture.

Other changes in the details of construction will readily occur to those skilled in the art and 40 may be made without departing from the spirit of the invention as recited in the appended claims.

From the foregoing description, taken in connection with the accompanying drawing, it is thought that the construction, combination and 45 advantages of my invention will be clear to those skilled in the art to which it appertains.

It will be seen from the foregoing that by the use of my invention clumsy stepladders which often cause accidents when putting articles away 50 or when removing same from high shelves may be done away with and the articles placed on the shelves or removed therefrom in a safer and quicker way than has been the practice heretofore.

- 55 What I claim is:

1. An implement of the character stated including a pole, a platform mounted on an end of the pole, a stationary tongue secured to the platform and projecting beyond the limits of the same, a bar slidably adjustably mounted on the pole and projecting above the platform, a tongue hingedly mounted on the end of said bar for swinging over said stationary tongue, means controlled by the user at a point remote from the platform for moving said hinged tongue downwardly and means for lifting said tongue when said last-named means is released.

2. An implement of the character stated including a pole, a platform mounted on an end of the pole, a stationary tongue secured to the platform and projecting beyond the limits of the same, a bar slidably adjustably mounted on the pole and projecting above the platform, a tongue hingedly mounted on the end of said bar for swinging over said stationary tongue, means con-

trolled by the user at a point remote from the platform for moving said hinged tongue downwardly and means for lifting said tongue when said last-named means is released, said platform having sides converging from said stationary tongue laterally, and guide elements on the sides of the platform which cooperate with the tongue moving means.

3. An implement of the character stated including a pole, a platform mounted on an end of the pole, a stationary tongue secured to the platform and projecting beyond the limits of the same, a bar slidably adjustably mounted on the pole and projecting above the platform, a tongue hingedly mounted on the end of said bar for swinging over said stationary tongue, means controlled by the user at a point remote from the platform for moving said hinged tongue downwardly and means for lifting said tongue when said last-named means is released, said controlled means comprising cords secured to said hinged tongue and passing through eyes located adjacent the lateral extremities of said platform downwardly to a place along the pole where the user can grasp the same.

4. An implement of the character stated comprising a pole, a platform mounted on an end of the pole, a stationary tongue secured to the platform and projecting beyond the limits of the same, a block secured to the platform and extending downwardly therefrom, a spacer between said block and said pole, means rigidly securing said block, said spacer and said pole together, a bar slidably and adjustably secured to said block to project above the platform, a tongue hingedly mounted on the upper end of said bar for swinging over said stationary tongue, means controlled by the user at a point remote from said platform for moving said hinged tongue downwardly, and means for lifting said tongue when said last-named means is released.

5. An implement of the character stated including a pole, a platform mounted on an end of the pole, a stationary tongue secured to the platform and projecting beyond the limits of the same, a bar slidably adjustably mounted on and offset from the pole and projecting above the platform, a tongue hingedly mounted on the end of said bar for swinging over said stationary tongue, means controlled by the user at a point remote from the platform for moving said hinged tongue downwardly and means for lifting said tongue when said last-named means is released, said stationary tongue being concaved.

6. An implement of the character stated including a pole, a platform mounted on an end of the pole, a stationary tongue secured to the platform and projecting beyond the limits of the same, a bar slidably adjustably mounted on the pole and projecting above the platform, said stationary tongue being recessed to straddle said bar, a tongue hingedly mounted on the end of said bar for swinging over said stationary tongue, means controlled by the user at a point remote from the platform for moving said hinged tongue downwardly and means for lifting said tongue when said last-named means is released, said stationary tongue having at least one finger at its outer end.

7. An implement of the character stated including a pole, a platform mounted on an end of the pole, a stationary tongue secured to the platform and projecting beyond the limits of the same, a bar slidably adjustably mounted on the pole and projecting above the platform, a tongue

hingedly mounted on the end of said bar for swinging over said stationary tongue, means controlled by the user at a point remote from the platform for moving said hinged tongue downwardly and means for lifting said tongue when said last-named means is released, said stationary tongue being concaved in cross section and said stationary tongue having at least one finger at its outer end.

19 8. An implement of the character stated including a pole, a platform mounted on an end of the pole, a stationary tongue secured to the platform and projecting beyond the limits of the same, a bar slidably adjustably mounted on and offset from the pole and projecting above the platform, a tongue hingedly mounted on the end of said bar for swinging over said stationary tongue, means controlled by the user at a point remote from the platform for moving said hinged tongue downwardly and means for lifting said tongue when said last-named means is released, said stationary tongue having a cover of a material different from that of the body of the tongue.

25 9. An implement of the character stated including a pole, a platform mounted on an end of the pole, a stationary tongue secured to the platform and projecting beyond the limits of the same, a bar slidably adjustably mounted on and offset from the pole and projecting above the platform, a tongue hingedly mounted on the end of said bar for swinging over said stationary tongue, means controlled by the user at a point remote from the platform for moving said hinged tongue downwardly and means for lifting said tongue when said last-named means is released, said stationary tongue being composed of metal sheathed wood.

40 10. An implement of the character stated including a pole, a platform mounted on an end of the pole, a stationary tongue secured to the platform and projecting beyond the limits of the same, a bar slidably adjustably mounted on the pole and projecting above the platform, a tongue hingedly mounted on the end of said bar for swinging over said stationary tongue, means controlled by the user at a point remote from the platform for moving said hinged tongue downwardly and means for lifting said tongue when said last-named means is released, said hinged

tongue including a body having a disk with a toothed rim projecting transversely to the plane of the disk.

11. An implement of the character described comprising a pole, a rhomboid-shaped platform mounted on an end of the pole, said platform having a recess in its rear edge, a block held in said recess and secured to said platform and extending below said platform, a spacer secured to said block and to said pole, bolts and nuts carried by the block, a vertically slotted bar held vertically adjustable on said block by said bolts and nuts, said sliding bar having a head, a tongue hingedly mounted on said head, a spring to move said tongue upwardly, a presser plate carried by said tongue, a stationary tongue having at least one finger and mounted on and projecting from said platform, guide eyes at the sides of said platform, and cables passed through said eyes and having an end of each secured to the hinged tongue to move it downwardly.

12. In an implement of the character stated, a pole, a platform mounted on an end of the pole and having a forwardly projecting tapered tongue-like portion, a bar slidably adjustably mounted on and offset from the pole and projecting above the platform, a tongue hingedly mounted on an end of said bar for swinging over said tongue-like portion to cooperate therewith, means controlled by the user at a point remote from the platform for moving said hinged tongue downwardly and means for lifting said tongue when said last-named means is released.

13. In an implement of the character stated, a pole, a platform mounted on an end of the pole and having a forwardly projecting tapered tongue-like portion, a bar slidably adjustably mounted on and offset from the pole and projecting above the platform, a tongue hingedly mounted on an end of said bar for swinging over said tongue-like portion to cooperate therewith, means controlled by the user at a point remote from the platform for moving said hinged tongue downwardly, means for lifting said tongue when said last-named means is released, said tongue-like portion being tapered on its under side, and a tongue removably secured on the upper face of said platform to overlie said tongue-like portion.
